His Attorney.

UNITED STATES PATENT OFFICE.

JULIUS W. HEGELER, OF LA SALLE, ILLINOIS.

APPARATUS FOR ELEVATING LIQUIDS.

SPECIFICATION forming part of Letters Patent No. 558,173, dated April 14, 1896.

Application filed October 4, 1895. Serial No. 564,593. (No model.)

To all whom it may concern:

Be it known that I, JULIUS W. HEGELER, of La Salle, in the county of La Salle and State of Illinois, have invented certain new and useful Improvements in Apparatus for Elevating Liquids, of which the following is a specification.

My invention relates to apparatus in which compressed air or gas is introduced into the lower part of a partially-submerged open-ended tube or pipe for elevating the liquid therein above the point of submergence; and the object of my improvement is to provide portable means for causing liquids to flow from a lower to a higher level in the process of manufacture without the use of suction-valves, said means being more especially adapted for use in the manufacture of sulfuric or other acids which are dangerous to handle and so destructive of the apparatus as to require its frequent inspection to prevent loss by leakage. I attain the object by the means illustrated in the accompanying drawings, in which—

25 Figure 1 is a side elevation of an apparatus embodying my improvement, the same being represented as suspended in a well-shaft. Fig. 2 is an enlarged detail showing partly in vertical section a fragment taken from the top part of the apparatus proper. Fig. 3 is an enlarged detail showing in side elevation a fragment taken from the bottom part. Fig. 4 is a cross-section.

The apparatus comprises a fold of pipe 35 whose ends are provided with suitable means for readily attaching and detaching the ends of similarly-formed induction and eduction pipes, an air-pipe communicating at one end by an air-tight connection with one member 40 of the fold above the bottom, the other end being provided with suitable means for readily attaching and detaching the similarly-formed end of a supply-pipe coming from a suitable source of compressed air, and a 45 hanger suitably connected with the fold and air-pipe, whereby they are united so as to be suspended in a well-shaft by the hanger while connected in use or lifted out of the well-shaft by the hanger when detached from the 50 induction and eduction pipe for inspection and repair.

In the drawings, A designates the fold of

pipe, which is made of lead, for transporting sulfuric acid, the ends *a* being flanged, whereby the similarly-flanged ends of the eduction-pipe A' and the induction-pipe A² may be readily connected and disconnected by means of screw-bolts *a'*.

B designates the air-pipe, also of lead, one end of which enters one member of the fold 60 at *b*, passing through an opening in the wall of the folded pipe A and being soldered in so as to form an air-tight communication therewith.

B' is the air-induction pipe shown in fragment, by which compressed air is brought from any suitable source of supply and delivered into the pipe B.

C designates the hanger, which comprises a rod of iron or other stout material provided 70 with an eye *c* for a cross-bar *c'*, by which it may be suspended from the cover D of the well-shaft D', and also with an eye *c²*, by means of which the hook of a lifting-derrick may be connected for lifting the apparatus 75 out of the well-shaft. The hanger is connected with the fold and the air-pipe by means of an intermediate lead tube *c³*, which is compressed upon the hanger-rod, so as to enter threads or other depressions made therein, whereby its surface is roughened or made so uneven that the tube compressed upon it will be firmly fixed thereto, and then soldered to the fold and compressed-air pipe 80 preferably along the entire length of the 85 hanger-rod, which is preferably extended along nearly the whole length of the fold.

When the liquid is introduced into the fold through the induction-pipe A², it will rise in the fold and in the air-pipe to the level of the 90 induction-pipe or the source of supply. In such condition a sufficient force of compressed air is turned on to force the liquid out of the air-pipe into the fold and cause it to rise in the eduction-pipe A' and flow out of the open 95 end thereof at the top into a suitable receptacle B² above the level of the supply. After the column of liquid in the member of the fold to which the air-pipe is attached has been forced out the air-pressure may be reduced 100 and will then form air-bubbles in that side of the fold, causing the liquid to rise in and be discharged from the open end of the eduction-pipe above the level of the supply.

What I claim is—

1. An apparatus for elevating liquids comprising a fold of open-ended pipe, and an air-pipe having one end connected with one member of the fold above the bottom, said fold and an air-pipe being united by a hanger for suspending them in and lifting them out of a well-shaft as specified.
2. An apparatus for elevating liquids comprising a fold of pipe provided with means for attaching and detaching an induction and

an induction extension to its opposite ends, an air-pipe having one end entered into one member of the fold above its bottom and the other end provided with means for attaching and detaching an induction extension, and a hanger provided with eyes and connected with the fold and air-pipe as specified.

JULIUS W. HEGELER.
